UNITED STATES PATENT OFFICE.

CARL FÖRSTER, OF NEW YORK, N. Y., ASSIGNOR TO PHILIP KORN, OF SAME PLACE.

DESIGN FOR A CHAIN.

SPECIFICATION forming part of Design No. 13,857, dated April 17, 1883.

Application filed February 15, 1883. Term of patent 7 years.

To all whom it may concern:

Be it known that I, CARL FÖRSTER, a subject of the Emperor of Germany, residing in the city, county, and State of New York, have 5 invented and produced a new and original Design for Chains, of which the following is a specification, reference being had to the accompanying drawing, forming part thereof, in which a piece of my newly-designed chain is 10 shown.

My newly-designed chain is formed of a series of flat oval links, A, and a series of oval or elliptical links, B. The links A and B are so arranged that they will be inclined to the 15 longitudinal axis through the center of the width of the chain, the flat links A being inclined in one direction, and the links B made with circular shanks and inclined in the opposite direction, as shown. Each link B passes 20 through two flat links A, one end of the link B being at the bottom of one link A, and the other end being at the top of the other link A, and a link A being held within the link B, so that the latter link A will be between the

former two links A, and so on throughout the 25 length of the chain, as shown. The flat links A overlap each other laterally, and the links B overlap each other vertically.

Having thus described my invention, I claim as new and desire to secure by Design Patent— 30

1. The herein-described design for chains, consisting of flat links A and links B, the links A being inclined to the longitudinal axis of the chain in one direction, and the links B being inclined in the reverse direction, the links 35 A B passing through each other, as set forth.

2. The herein-described design for chains, consisting of flat links A and links B, the links A and B being inclined to the longitudinal axis of the chain in opposite directions, and the 40 links B passing through alternating links A, and the links A being held within the links B, passing through the adjoining links A at opposite ends, as set forth.

CARL FÖRSTER.
